US00D682158S

(12) **United States Design Patent**
Canni et al.

(10) **Patent No.:** US D682,158 S
(45) **Date of Patent:** ** May 14, 2013

(54) **REVERSE TRIKE**

(75) Inventors: **Adam J. Canni**, Fleming Island, FL (US); **Clyde T. Sliger**, Culpeper, VA (US); **Merrill C. Hall**, Culpeper, VA (US)

(73) Assignee: **Tanom Motors, LLC**, Culpeper, VA (US)

(**) Term: **14 Years**

(21) Appl. No.: **29/405,225**

(22) Filed: **Oct. 31, 2011**

(51) **LOC (9) Cl.** 12-08

(52) **U.S. Cl.**

USPC **D12/85**

(57) **CLAIM**

The ornamental design for a reverse trike, as shown and described.

DESCRIPTION

FIG. 1 is a front left perspective view of the reverse trike according to an embodiment;

FIG. 2 is a rear left perspective view of the reverse trike illustrated in FIG. 1;

FIG. 3 is a left side view of the reverse trike illustrated in FIG. 1, the right side view being a mirror image of the left side view;

FIG. 4 is a front end view of the reverse trike illustrated in FIG. 1;

FIG. 5 is a rear view of the reverse trike illustrated in FIG. 1; and,

FIG. 6 is a top view of the reverse trike illustrated in FIG. 1. The broken lines immediately adjacent the shaded areas represent the bounds of the claimed design while all other broken lines are directed to environment and are for illustrative purposes only; the broken lines form no part of the claimed design.
